FLUID SEPARATOR

Paul M. Brister, Madison, N. J., assignor to The Babcock & Wilcox Company, Rockleigh, N. J., a corporation of New Jersey

Application February 11, 1943, Serial No. 475,475

4 Claims. (Cl. 183—83)

1

This invention relates to separators for fluids of different densities, and, more particularly to a centrifugal fluid separator.

A preferred embodiment of the invention involves a substantially circular whirl chamber into which a high velocity stream of steam and water mixture is tangentially discharged so as to set up a whirling motion within the chamber. As a consequence of the centrifugal action within the whirl chamber steam is separated from the water and the separated steam exits through a central upper outlet while the separated water is discharged through a lower outlet.

An object of the invention is to provide for the control of the outflow of separated steam from the steam outlet in such a manner as to collect entrained moisture particles on the surface of a perforated member arranged across the steam flow path and drain the collected particles to a lower central whirl chamber position at which a relatively low pressure condition exists.

It is also an object of the invention to so arrange the extent and proportions of perforated members to uniformly distribute the steam flow and maintain the separator outlet velocity below a critical value so that moisture particles will not be entrained in the steam.

The invention contemplates the use of the illustrative separator in a high pressure steam generator, to improve circulation and to enable the generator to operate under high and/or unstable drum water level conditions and still supply steam of high quality.

The invention will be described with reference to the accompanying drawings in which a preferred embodiment of the invention is shown, and other objects of the invention will appear as the description proceeds.

In the drawing:

Fig. 1 is a diagrammatic view in the nature of a vertical section showing a steam generator in connection with which the invention is employed;

Fig. 2 is a detailed view in the nature of a vertical transverse section through the steam and water drum of the Fig. 1 installation;

Fig. 3 is a vertical section of the illustrative separator, and

Fig. 4 is a horizontal, or plan, section of the separator on the line 4—4 of Fig. 3.

The illustrative separator includes a substan-

2

tially circular whirl chamber 10 formed by a shell or casing 11 and having an inlet 12 through which a mixture of steam and water is discharged substantially tangentially and at high velocity into the whirl chamber.

The introduction of a high velocity mixture of steam and water sets up a vertical action of the mixture with the water thrown outwardly against the cylindrical whirl chamber wall by the centrifugal effect while the steam which is of lower density is displaced toward the central portion. This action also induces a zone of lower pressure at the axial center of the whirl chamber.

Steam is separated from the water within the whirl chamber, the steam passing upwardly through a central steam circular outlet 14 defined by a cylindrical member 14a and then through a scrubber or multiple steam and water separator 16 spaced from the top of the whirl chamber to provide the auxiliary lateral steam outlet 17. The separated water is discharged downwardly through circumferentially arranged outlets 18 between successive helical vanes such as those shown at 20 and 22.

The member 14a is a shield between the upper part of the inlet 12 and the perforated hollow cone baffle 24.

To minimize the discharge with the separated steam of entrained droplets of water, an inverted perforated metallic cone 24 is disposed with its apex within the whirl chamber and its base 26 is secured to the top flange 28 of the whirl chamber casing as clearly indicated in Fig. 3 of the drawing. The sum of the flow areas of the perforations in the cone 24 is at least as great as the free flow area of the circular steam outlet 14, and the perforated cone accomplishes the following results:

(a) It equalizes the outlet steam velocity at various transverse positions across the outlet 14 by introducing the flow restrictive effect of the plurality of spaced orifices, while eliminating the major portion of the angular movement of the steam flow.

(b) It acts as a barrier to collect by cohesion any entrained droplets of water tending to pass upwardly with the steam.

(c) It drains the collected water toward a position centrally of the vortex within the chamber.

(d) It returns the collected water to the water

in the whirl chamber at a zone of decreased pressure so as to minimize reentrainment.

(e) By providing a uniform steam velocity condition approaching the multiple plate separator 16, it equalizes the loading of the separator resulting in an improved separating effect.

(f) It directly affects the functioning of the separator 16 by breaking up any slugs of water which might otherwise attempt to pass through that separator, under some conditions. In this way the cone 24 permits the multiple plate separator to function in the most effective manner.

Preferably the vanes 20 and 22 between successive outlets for separated water are secured in an annular passage at the bottom of the whirl chamber casing 11. This annular passage is defined by the upright wall of a pan 42 and the bottom portion of the wall of the whirl chamber as indicated in Figs. 2 and 3.

A number of separators may be secured within the steam and water drum 50, and, for this purpose, the steam and water inlet structure 12 for each separator is provided with a heavy flange 52 for securement to a similarly formed flange 54 secured to the upright wall 56 of an inlet compartment 58.

Steam and water mixtures are discharged into the inlet compartment 58 by the steam generating tubes 60-63, and separated water from the whirl chambers 10 passes downwardly from the water space 49 of the drum 50 through the down-comers 51 and other external downcomers which are not shown in the drawing. Steam from the separator 10 passes from the drum through a steam offtake 74 and is conducted thence to a superheater which is indicated in Fig. 1 as consisting of two sections 78 and 80.

The main boiler furnace 82 is fired by burners 83-86 and the auxiliary, or superheater furnace 90, is independently fired by the burners 92-94, the two furnaces being separated by the superheater and the steam generating tubes 60 and 61 which directly connect the water drum 100 with the inlet compartment 58 of the drum 50.

Furnace gases from the main furnace 82 pass across a bank of tubes directly connecting a submerged drum 102 to the inlet compartment 58. Some of these tubes are indicated at 62 and 63 in Fig. 1. Beyond these tubes the gases next contact the tubes of an economizer 104 disposed within a gas pass 106 leading to a flue.

When the superheater furnace is operating, furnace gases therefrom pass across the tubes of the superheater and then across the upper parts of the tubes 61-63 where they join the gases from the main furnace.

What is claimed is:

1. In a fluid separator, a casing providing an upright whirl chamber with an upper perimetral inlet through which there is a high velocity tangential flow of a mixture of fluids of different densities, the casing having a top rim structure presenting an upper whirl chamber outlet for separated fluid of lesser density, the upper outlet communicating with the central part of the whirl chamber, an auxiliary separator including spaced fixed members and disposed above said upper outlet so as to provide an auxiliary outlet between the top of the whirl chamber and the auxiliary separator, a lower whirl chamber outlet for a separated fluid of greater density, and an inverted conoidal baffle extending downwardly into the whirl chamber and across the upward path of all of the lesser density fluid toward the upper whirl chamber outlet, the baffle

extending entirely across said upper whirl chamber outlet at a level below that of the auxiliary outlet and having multiple openings or perforations over its area, said baffle also having its perforated side portions converging downwardly from the perimeter of said upper outlet toward a position centrally of the whirl chamber and being so constructed that the total flow area of its perforations is at least as great as the free flow area of the upper whirl chamber outlet.

2. In a fluid separator, a casing presenting an upright whirl chamber with an inlet through which there is a high velocity tangential flow of a mixture of fluids of different densities, the casing having a rim structure at the top of the whirl chamber forming an upper outlet for separated fluid of lesser density, the casing also having a bottom structure forming a lower outlet for a separated fluid of greater density, an auxiliary separator including spaced fixed elements and spaced above said upper outlet so as to leave an auxiliary top outlet beneath the auxiliary separator and laterally of said upper outlet, and an inverted conoidal baffle extending downwardly into the whirl chamber and across the path of all fluid flowing toward said auxiliary outlet and the upper whirl chamber outlet, said baffle having side portions converging downwardly toward a position centrally of the whirl chamber and being so constructed that the total flow area of its perforations is at least as great as the free flow area of the upper whirl chamber outlet, the conoidal baffle being also secured to the top of the whirl chamber so that it is disposed entirely below the level of the auxiliary top outlet.

3. In a centrifugal separator for different density fluids one of which is a liquid, a casing forming an upright circular whirl chamber and a whirl chamber inlet through which there is a tangential high velocity flow of a mixture of fluids of different densities, an upper whirl chamber outlet for separated fluid of lesser density, a lower whirl chamber outlet for separated liquid, a perforated baffle having the surface of an inverted perforated hollow cone extending downwardly into the whirl chamber from said upper whirl chamber outlet and having a perimetric base secured to the top of the whirl chamber casing around the perimeter of the upper whirl chamber outlet, and a curved shield interposed relative to the baffle and the upper part of said inlet, the sum of the flow areas of the perforations of the hollow cone being at least as great as the free flow area of the upper whirl chamber outlet and the whirl chamber and the baffle being of such construction that they form downwardly diverging walls for the fluid space therebetween.

4. In a centrifugal separator for fluids of different densities, a casing forming an upright whirl chamber and a whirl chamber inlet through which there is a high velocity flow of a mixture of fluids of different densities, the casing having a top rim structure forming an upper whirl chamber outlet for separated fluid of lesser density, a multiple plate auxiliary separator disposed above the upper whirl chamber outlet, the separator and its support being spaced from the casing and thereby forming an auxiliary whirl chamber outlet disposed laterally of said upper outlet and above the whirl chamber, the casing having a bottom structure forming a lower whirl chamber outlet for a separated fluid of greater density, said lower outlet being limited to a marginal or circular zone around the bottom of the whirl cham-

ber casing, and a perforated baffle having an inverted conoidal surface with its apex presented downwardly within the whirl chamber vortex, the baffle having its base secured to and terminating at the top of the whirl chamber casing in such a manner that all fluid flowing to the auxiliary and upper outlets must pass through the baffle openings, the sum of the flow areas of the openings through the baffle being at least as great as the free flow area of said upper whirl chamber outlet.
